UNITED STATES PATENT OFFICE.

WILLIAM C. HAESSE, OF MILWAUKEE, WISCONSIN.

TRACK-SANDER SPOUT.

1,143,824.

Specification of Letters Patent. Patented June 22, 1915.

Application filed December 7, 1914. Serial No. 875,779. **REISSUED**

To all whom it may concern:

Be it known that I, WILLIAM C. HAESSE, a citizen of the United States, and resident of Milwaukee, in the county of Milwaukee and 5 State of Wisconsin, have invented new and useful Improvements in Track-Sander Spouts, of which the following is a description, reference being had to the accompanying drawings, which are a part of this specification.

10 This invention has for its object to provide a spout for track sanders of electric railway cars or the like which will be flexible and extensible and capable of turning to 15 permit its lower end to be held in a fixed position close to and in front of the car wheels while its upper end is attached to the car body in communication with the sand hopper.

20 Another object of the invention is to provide such a spout for track sanders which may be constructed of metal so as to be more durable and efficient and consisting of 25 articulating segments with each segment overlapping the edge of the next segment below, both inside and outside of the spout so as to shed the sand traveling through the interior of the spout and so as to shed water and snow on the outside of the spout.

30 Another object of the invention is to further protect the spout against freezing by providing self closing lips at its discharge end that will prevent the introduction of snow or the like.

35 With the above and other objects in view the invention consists in the track sander spout as herein claimed and all equivalents. Referring to the accompanying drawing the figure constitutes a central sectional 40 view of a track sander spout constructed in accordance with this invention.

In this drawing 10 represents the floor 45 of the car body containing a sand box or hopper, not shown, with an opening 11 through the floor through which the sand is discharged, as by a blast of compressed air as usual. A funnel-shaped plate 12 surrounds the opening 11, and between it and a flanged ring 13 is mounted a flanged tubular swivel section 14 capable of turning on 50 its axis and having the tapering portion of the funnel entering the flaring upper end thereof so that sand passing through the opening 11 is guided by the funnel to the bore of the swivel section 14. A flange 15 surrounds the lower end of the tubular

swivel section 14 and is spaced therefrom to form an annular groove 16 within which at diametrically opposite points are pivot pins 17 pivotally connecting the upper edge 60 of a sector-shaped tubular section 18 having side walls of an inverted V-shape in cross section. The inner and outer diverging tubular flanges of the section 18 form between them an annular groove 19 to receive the 65 upper edge of another tubular section of similar construction, and so on throughout a series of tubular sections similarly positioned with their corresponding parts alined so as to produce a curvature or bend and 70 form a flexible elbow, the pivot connections 17 being in alinement along the opposite sides of the bend. The play of each tubular section in the groove of the section thereabove enables the angularity of the bend to 75 be greater or less without disturbing the tubular form of the elbow and without opening the joints.

The spout is preferably composed of two flexible elbows reversely bent and connected 80 by an intermediate telescoping section comprising an upper tubular member 20 with a single edge at its upper end pivotally connected in the groove of the lowermost section of the upper elbow and with its lower 85 end formed of concentric tubular parts spaced apart to receive the lower tubular member 21 which has a telescoping fit therebetween and has a pair of concentric diverging flanges 22 at its lower end to receive the 90 upper edge of the uppermost section of the lower elbow.

The lowermost section of the lower elbow comprises a tubular member 23 surrounded by a flanged collar 24 secured 95 thereto and swivelly mounted in a ring 25 on a bracket 26 carried in any suitable manner by the truck 27 of the car directly in front of the car wheel 28 and terminating a short distance above the rail 29. At the 100 lower end of the tubular member 23 there is an annular flange 30 concentric therewith and spaced therefrom to form a comparatively deep annular groove in which are pivotally mounted a pair of curved lip members 31, the pivot points 32 thereof being so positioned relative to the center of gravity of the lip members as to cause said members to normally hang in a closed position, as shown, but permitting of their swinging 105 away from each other under the weight of sand discharged through the spout, as shown

by dotted lines, and then serving to spread the sand over the head of the rail 29.

By means of this invention the sand from the sand box is conducted through an all metal spout to a point close to the rail and directly in front of the car wheel, and this, irrespective of the direction of travel of the car, that is to say, the point of delivery remains the same when the car body is shifted relative to the car truck on turning curves and when the car is traveling on a straight track.

The vertical and horizontal swinging movements of the car body with relation to the truck in no way affect the operation of the discharge spout, for the lower member thereof remains in its fixed position and the change in position of the upper member is permitted by the telescoping of the members 20 and 21, the pivotal movements of all members in their connection with each other and the swivel movements of the members 14 and 23. Not only are all of the surfaces so related as to avoid the formation of pockets or ledges within the spout for holding sand or retarding its flow, but on the exterior of the spout they are so overlapped as to shed water and prevent the parts freezing. Also, the automatically closing swinging lip members 31 prevent the spout becoming clogged with sand and ice; so that the device will remain operative at all times, and being constructed of metal it will be durable and not liable to injury.

What I claim as new and desire to secure by Letters Patent is:

1. A spout for track sanders, comprising a flexible tube formed of sections pivotally connected together, each section having a groove in its lower edge receiving the upper edge of the section therebeneath, means on the uppermost section for connection with a car body and means on the lowermost section for connection with a car truck.

2. A spout for track sanders, comprising a flexible tube formed of sections pivotally connected together, each section having its side walls of V-shape in cross section with its single edge pivotally connected between the double edge of the section thereabove, means on the uppermost section for connection with a car body and means on the lowermost section for connection with a car truck.

3. A track sander spout, comprising a pair of oppositely curved flexible elbows connected with the car body and the car truck

respectively, each elbow being formed of sector-shaped tubular members pivotally connected together, the upper single edge of each member fitting between a pair of lower divergent edges of the member thereabove, and means for connecting the elbows together.

4. A spout for track sanders, comprising a pair of flexible tubular elbows connected respectively to a car body and a car truck, each elbow comprising a series of sector-shaped tubular members pivotally connected together, each member having a single upper edge and a pair of divergent flanges for the lower edge forming an annular groove between them and each member having its upper edge pivotally connected within the annular groove of the member thereabove, a tubular member having its upper edge pivotally connected in the annular groove of the lowermost member of the upper elbow and having an inner and an outer wall with an annular space between them, and a tubular member slidably fitting within said annular space and having an annular groove at its lower end within which is pivotally connected the upper edge of the uppermost member of the lower elbow.

5. A spout for track sanders, comprising a funnel plate, a flanged ring secured thereto, a flanged swivel member fitting between the funnel plate and the flanged ring and capable of turning, said swivel member having an annular groove at its lower edge, a flexible elbow of articulated interfitting members having tongued and grooved upper and lower edges respectively, a similar flexible elbow having telescoping connection with the first mentioned flexible elbow, a tubular member at the lower end of the second flexible elbow, a flanged collar thereon, a ring within which the flanged collar is swivelly mounted and adapted for connection with a car truck, said tubular member having an annular groove at its lower edge, and curved lip members pivotally mounted within the annular groove and normally engaging each other to close the end of the spout but opening by the weight of the sand to distribute the sand on the rail.

In testimony whereof, I affix my signature, in presence of two witnesses.

WILLIAM C. HAENSE.
